[57] CLAIM

The ornamental design for a combined brush handle
and back unit and scraper therefor, as shown.

DESCRIPTION

FIG. 1 is a top plan view of a combined brush handle
and back unit and scraper therefor showing my new
design;

FIG. 2 is a right side elevational view thereof;

FIG. 3 is a front end elevational view thereof;

FIG. 4 is a rear end elevational view thereof;

FIG. 5 is a bottom plan view thereof; and
FIG. 6 is a perspective view as seen from the top and
left side thereof.

FIG. 4

FIG. 5

FIG. 3
